UNITED STATES PATENT OFFICE.

NICHOLAS GUGLIUZZI, OF ANSONIA, CONNECTICUT.

CURTAIN FIXTURE.

Application filed January 15, 1926. Serial No. 81,427.

This invention relates to a new and improved curtain fixture.

It is the object thereof, among other things, to provide a fixture that will not only conveniently support a window shade but adapted also, if desired, to support a plurality of sets of curtains, the mechanism of which will be simple in its design, economical to construct, can be positioned on the window frame without the use of screws, nails, or similar fastening devices, and adjusted for any width of shade or curtain.

Other features of the invention will be apparent from the following specification and accompanying drawings, wherein a preferred embodiment of the invention is described and illustrated.

My invention consists in a curtain fixture having certain details of construction and combinations of parts, as will be hereinafter described and more particularly pointed out in the claims.

In the drawings, wherein like numerals of reference designate like parts in the several figures;

Figure 1 is an elevation of a portion of a window frame with my improved device attached thereto with which is associated a window shade and two curtain rods;

Figure 2 is a plan view thereof, the parts in section being portions of the window frame;

Figure 3 is a perspective view of that portion of the device connected with one side of the window frame;

Figure 4 is a transverse sectional view thereof, the parts in section being taken generally upon line 4-4 of Figure 3;

Figure 5 is a detail, perspective view of a portion of the curtain plate, curtain rod and the means for separably securing the same together;

Figure 6 is a fragmentary detail view of one end of a curtain rod, in which is positioned the mechanism for separably securing the same to the curtain plate;

Figure 7 is an end view thereof;

Figure 8 is a plan view of the support plug; and

Figure 9 is an elevation of a modified form of curtain plate.

In the embodiment of this invention, the mechanism for both sides of the window frame are the same, and as shown in Figure 3, comprise a base member 10 having a head portion 11 at one end with prongs 12

thereon and a hook 13 near the opposite end, to which is connected one end of a coil spring 14, the opposite end being connected with a similar hook on the base member at 60 the opposite side of the window frame.

Preferably integral with and near the central portion of the base member is a guard plate 15, through which is a slot 16 and between which and the body of the base member 10 is an open space 17. Movably connected with the base member is a shade arm 18 for supporting the window shade 19. The lower portion of these arms is of conventional shape. In a set there is 70 one having a rectangular opening 20 therethrough and the other a circular hole, as is usual.

The upper portion of each of these arms is provided with a foot plate 21 that is within 75 the open space 17 and a flange 22 at one edge. The open space between the flange 22 and the portion 23 of the arm at the opposite end of the plate 21 is substantially the same as the width of the plate 15, whereby the 80 intermeshing engagement of these parts provides a rigid support for the shade arm.

Projecting through an opening in the plate 21 and slot 16 is a screw 24 having a thumb nut 25 thereon. The arm 18 is thus slidably 85 mounted upon the base member 10 and secured in any of its adjusted positions relatively thereto.

The curtain plate 26 has a leg portion 27 which is substantially the same width as the space between the inner face of the end wall 28 of the plate 15 and the lugs 29 integral with the base member, and a head portion 30 which is provided with one or more openings 31 therethrough. This plate is readily 90 attached to the base member by projecting the leg portion 27 downwardly between the end of the guard plate 15, the lugs 29, with the shoulder 32 resting on top of the upper lug, substantially as shown in Figure 3. 100

The curtain rods 33 shown herein are of the conventional extension type, made usually of hollow tubing. In each end of each of these rods is a support plug 34, which has two spring arms 35 and a plate portion 105 36, which extends both below and above the spring arms 35, the upper end terminating in a head 37 connected by a neck portion 38. The width of the neck portion and that of the plate 36 adjacent thereto are substantially the same as that of the parallel sided portions of the opening 31, and the head por-

tion 37 is substantially the same shape as that of the upper portion of the same opening so that it may be readily passed therethrough for the purpose of assembly. When 5 so assembled the neck portion 38 rests upon the lower edge of the opening 31, and the opposite sides of the head 37 are upon opposite sides of the opening 31, and thereby locked against disengagement therefrom. 10 Thus a curtain rod of any length may be readily attached or detached and one or more may be utilized, as desired, the only limitation being the number of openings in the curtain plate 26. As these curtain plates 15 are easily positioned, it is quite a simple matter to substitute new ones to meet any requirement.

In Figure 9 there is shown a modified form of curtain plate, wherein the openings 20 39 therethrough are substantially rectangular in shape, and connected with the adjacent edge of the plate by a slot 40. The plug 34 is assembled with this form of plate by sliding the neck portion 38 through the 25 slot 40.

Within the scope of the appended claims, minor changes and alterations may be made, aside from those herein suggested, and I would therefore have it understood that I 30 do not limit myself to the exact construction herewith shown and described, but claim all that falls fairly within the invention.

Having described my invention, what I 35 claim as new and desire to secure by Letters Patent, is:—

1. In a curtain fixture; a body member having a base portion, a head portion at one end, a guard plate integral with the base 40 portion and separated therefrom between its ends by an open space; a curtain plate separably connected with the body member, having an opening therein; and a support plug projecting through the opening and thereby having a separable engagement with the curtain plate.

2. In a curtain fixture; a body member having a base portion with lugs formed thereon; a head portion at one end; a guard 50 plate integral with the base portion and separated therefrom between its ends by an open space; a curtain plate having a leg portion which when the plate is assembled

with the body member projects through said open space between said lugs and an end 55 wall of the guard plate; and a support plug projecting through the opening and thereby having a separable engagement with the curtain plate.

3. In a curtain fixture; a body member 60 having a base portion with lugs formed thereon; a head portion at one end; a guard plate integral with the base portion and separated therefrom between its ends by an open space; a substantially L-shaped curtain 65 plate connected with the body member, one of the arms of which projects through said open space and between said lugs and an end wall of the guard plate, said curtain plate having an opening therethrough; and 70 a support plug, one portion of which projects through the opening in the plate and thereby provides a separable engagement therewith.

4. In a curtain fixture; a body member 75 having a base portion with lugs formed thereon; a head portion at one end; a guard plate integral with the base portion and separated therefrom between its ends by an open space; a substantially L-shaped curtain 80 plate connected with the body member, one of the arms of which projects through the said open space and between said lugs and an end wall of the guard plate, said curtain plate having an opening through the other 85 arm; and a support plug, one portion of which projects through the opening in the plate and thereby provides a separable engagement therewith.

5. In a curtain fixture; a body member 90 having a base portion, a head portion at one end, a guard plate integral with the base portion and separated therefrom between its ends by an open space; a curtain plate 95 separably connected with the body member, having an opening therein; and a support plug projecting through the opening and thereby having a separable engagement with the curtain plate, the support plug having substantially parallel spring arms terminating at one end in a plate portion formed with a head, and a connecting neck portion.

In testimony whereof, I have hereunto affixed my signature.

NICHOLAS GUGLIUZZI.
